REFRIGERATING APPARATUS

Edward B. Newill, Dayton, Ohio, assignor to
General Motors Corporation, Dayton, Ohio, a
corporation of Delaware

Application July 20, 1935, Serial No. 32,415
Renewed November 5, 1937

6 Claims. (Cl. 312—173)

This invention relates to refrigerating apparatus and particularly to refrigerating cabinets of the household type.

An object of the present invention is to provide an improved food supporting shelf arrangement within the storage compartment of a household refrigerator cabinet.

Another object of the present invention is to provide a shelf arrangement for a household refrigerator cabinet which includes a plurality of shelf portions that can be selectively moved into various positions to modify the arrangement to meet different food storage requirements.

A further object of the invention is to provide an improved shelving apparatus for a household refrigerator cabinet having a predetermined amount of shelf food supporting surface or area and when altered to afford a different arrangement of the storage of food products in the refrigerator the same predetermined total shelf food supporting surface is available for supporting food products in the food compartment of the cabinet.

In carrying out the foregoing objects it is a still further object of the invention to provide an improved shelf arrangement for a refrigerator cabinet which will, if desired, permit the storage of food products in the same manner as in conventional refrigerators while at the same time permitting the storage of additional tall bottled beverages and the like adjacent the front edge of one of the shelves of the shelf arrangement and which will also provide for the ready removal of products stored in the refrigerator cabinet by utilizing portions of the shelf arrangement, removed from other portions thereof to provide space for the storage of tall bottled beverages, as food shelves or supports on the door affording access to the interior of the refrigerator cabinet.

Further objects and advantages of the present invention will be apparent from the following description, reference being had to the accompanying drawings, wherein a preferred form of the present invention is clearly shown.

In the drawings:

Fig. 1 is a front view of a refrigerator cabinet showing the food compartment door in open position and disclosing an arrangement of shelves in the food compartment constructed in accordance with the present invention;

Fig. 2 is an enlarged vertical sectional view through the refrigerator cabinet taken on the line 2—2 of Fig. 1;

Fig. 3 is a fragmentary sectional view, similar

to Fig. 2, and shows the shelving in a rearranged position;

Fig. 4 is a horizontal sectional view through the refrigerator cabinet taken on the line 4—4 of Fig. 3;

Fig. 5 is an enlarged sectional view taken on the line 5—5 of Fig. 4 showing the construction of a portion of one of the shelves of the shelf arrangement of the present invention; and

Fig. 6 is a view similar to Fig. 5 showing a movable member attached to the shelf portion in a raised position.

Referring to the drawings, for the purpose of illustrating my invention, I have shown in Fig. 1 thereof a refrigerator cabinet of the household type generally designated by the reference character 10. The cabinet 10 includes a plurality of any suitably insulated walls 11 adjacent to and surrounding a metallic member 12 which forms a liner for the food storage compartment or chamber 13. The edges of the open side of the food compartment liner 12 may be secured to the door opening frame of the cabinet 10 in any suitable and well-known manner. A door 14 pivotally mounted upon cabinet 10 is provided for closing the access opening leading to the interior of compartment 13. An evaporator or cooling element 16 of any conventional design is mounted in the compartment 13 by being suspendingly supported from the top wall thereof. This cooling element is adapted to be connected with a suitable refrigerant liquefying and circulating unit (not shown) in a well-known manner so as to cause the element to produce a refrigerating effect for cooling chamber 13 and causing circulation of air therein.

The chamber 13 is partitioned or divided into a plurality of superimposed horizontally extending food storage spaces or compartments by a plurality of shelves generally designated by the reference character 17. Certain of the shelves 17 are formed by a shelf arrangement 18 comprising a shelf portion 19 and another shelf portion 20 which forms a complementary part of the shelf portion 19 in the arrangement 18. All of the shelves 17 provide, within chamber 13 of cabinet 10, a predetermined amount of shelf food supporting surface or area which is desired to be maintained within the cabinet irrespective of various changes in the shelving for permitting different food storage arrangements in the cabinet. It will be noted that in Fig. 3 of the drawings the two lower shelves are formed by the shelf arrangements 18 and that these shelves 18 are arranged to provide flat horizontally disposed

food supporting surfaces or areas occupying substantially all of the cross-sectional area of chamber 13 as is common in conventional refrigerators. When the shelves 18 are arranged as shown in Fig. 3 the refrigerator cabinet 10 is provided with a predetermined maximum amount of shelf food supporting surface and also a tall bottled beverage storage space adjacent the left side of the evaporator or cooling element 16 as viewed in Fig. 1.

10 Each of the shelf portions 19 of the shelf arrangements 18 comprise a metal rim member 21 having a plurality of cross pieces 22 secured thereto by soldering or welding same. These portions 19 of shelves 18 are provided with mounting studs preferably of soft resilient material adjustably secured to extensions 24 welded to rim 21 (see Fig. 4). The studs 23 are adapted to engage the walls, or to fit into depressions provided in the walls, of liner member 12 to stationarily secure the shelf portions 19 of shelves 18 within compartment 13. It will be noted that the front edge of shelf portions 19 are spaced from the front of the chamber 13 and from the inner surface of door 14. This space is normally adapted to be occupied by the movable shelf portions 20 of the shelf arrangements 18. Brackets or sockets 26 are welded or otherwise secured to the rim 21 of shelf portion 19 and other brackets or sockets 27 similar to the brackets or sockets 26 are secured in any suitable manner to the inner wall of door 14. The detachable or movable shelf portions 20 of the shelf arrangements 18 include a rim member formed by a back rod piece 28 and a front U-shaped rod piece 29 (see Figs. 4, 5 and 6). The ends of the back rod piece 28 are bent downwardly as at 30 to provide legs or extensions which are adapted to fit in openings provided in the brackets or sockets 26 and 27 to firmly support the shelf portions 20 in various positions. A plurality of cross rods 31 extend from the back rod 28 to the front rod 29 and these cross rods have a depression 32 formed therein for a purpose to be presently described. The cross rods at each side of the plurality of rods 31 thereof have an outwardly extending portion bent as at 33 provided thereon for a purpose to be also presently described. At each end of the movable shelf portion 20 of the shelf arrangement 18 an inverted U-shaped wire member 34 has its leg portions welded or otherwise secured to the rod pieces 28 and 29 so as to firmly hold the member 34 in a vertically disposed position to provide guide-rails at the ends or sides of the shelf portion 20. When the shelf portion 20 of the shelf arrangement 18 is carried by the door 14 of cabinet 10 it is desired to provide a guide-rail along the edge of the shelf portion 20 to prevent food products or other articles placed on this shelf portion from rolling or falling therefrom during movement of the door. Therefore I provide a wire member 36 with looped portions 37 which surround the rod piece 29. It will be noted (see Figs. 5 and 6) that the wire guide-rail or member 36 is movable or adjustable relative to the shelf portion 20 and that this movability is for a purpose to be presently described. It is obvious (see Fig. 6) that when the wire member 36 is elevated it strikes the extensions 33 provided on two of the wires 31 and thus the extensions 33 form a stop for preventing articles stored on the shelf portion 20 from pushing the guide-rail 36 out of its vertical position.

70 As before stated the storage chamber 13 has a predetermined maximum of shelf food support-

ing surface or area and is also provided with a storage space of predetermined size for the reception of tall bottled beverages. However, it quite frequently occurs that more bottled beverages are desired to be stored in chamber 13 than 5 can be accommodated in the bottle storage space originally provided therein. It is also desirable to maintain the total predetermined shelf food supporting surface or area within chamber 13 of cabinet 10 even when it is desired to store 10 additional bottled products therein. My invention is therefore particularly directed to a novel shelf arrangement which will permit the carrying out of these desirabilities. In other words my invention permits an additional quantity of 15 tall bottled beverages to be stored in the storage chamber of a refrigerator cabinet than can be ordinarily accommodated therein without depriving the user of valuable shelf food supporting surfaces. To carry out these requirements or desirables the function and rearrangement of the shelving arrangement disclosed and herein previously described will now be explained.

My improved shelving arrangement may be positioned or arranged as shown in Fig. 3 of the 25 drawings to provide a conventional flat shelf which occupies substantially all of a horizontal cross-sectional plane of the chamber 13. When in this position the movable shelf portion 20 is carried by and forms a complementary part of 30 the stationary mounted shelf portion 19 of the shelf arrangement 18 and is positioned in the space between the front edge of shelf portion 19 and the door 14. The movable guide-rail 36 provided on shelf portion 20 is moved down- 35 wardly into the position shown in Fig. 5 of the drawings so that the longitudinal portion thereof fits into the depression 32 provided in cross pieces 31 to provide a flat shelf surface and to eliminate the necessity of lifting food products 40 over the guide-rail during removal thereof from the flat shelf 18 in the arrangement shown in Fig. 3. Assuming that all of the shelf food supporting surfaces of the arrangement is occupied and also that the space for tall bottled beverages or the like, adjacent the cooling element 16, is filled and it is desired or required to place more bottled beverages in the refrigerator cabinet 10. The food products stored on the movable shelf portion 20 of the shelf arrangements 50 18 are therefore temporarily removed therefrom. The movable complementary shelf portions 20 of the shelf arrangements 18 are then detached from the stationary shelf portion 19, by removing the legs or depending portions 30 of shelf portion 20 from the holes in the brackets or sockets 26, and are turned around and moved upwardly so that the legs or depending portions 30 on the shelf portion 20 register with and may be placed in the openings provided in the brackets or sockets 27 secured to door 14. After the shelf portions 20 have been secured to door 14 the guide-rail 36 provided on shelf 20 is raised into the position shown in Fig. 6 to form a basket-like shelf on the door. The food products that 65 were temporarily removed from the shelf portions 20 are then to be replaced thereon for storage in compartment 13 and are therefore easily accessible when door 14 is opened. By the arrangement just described it will be apparent 70 that a relatively tall space has been provided adjacent the front edge of the stationary shelf portion 19 for the reception in a vertical position of bottled beverages (see Fig. 2). This arrangement to provide more space in the chamb- 75

ber 13 for tall bottled beverages does not deprive the user of the maximum food supporting surfaces in the refrigerator cabinet since the same total horizontally disposed shelf area is maintained therein by attaching the complementary shelf portions 20 of the shelf arrangements 18 to the door 14. The shelf arrangements disclosed may, if desired, be used in the rearranged position as described and shown in Figs. 1 and 2 of the drawings at all times, regardless of whether the space adjacent the front edge of the stationary shelf portion 19 is to be used for the storage of bottled beverages or not, to afford up-to-date storage and easy accessibility of small food products or articles which are frequently used during the preparation of a meal and which ordinarily become concealed in conventional refrigerators by being moved or placed behind other larger objects in the food chamber.

20 From the foregoing it will be seen that I have provided an improved shelving arrangement for household refrigerator cabinets that can be selectively and alternatively moved into various positions within the storage chamber of the cabinet 25 to meet different food storage requirements. My improved shelf arrangement can be altered or changed to meet various food storage requirements without eliminating any of the shelf food supporting surfaces or areas originally provided 30 in the food chamber. Thus my shelving arrangement provides additional space within a refrigerator cabinet for the storage of tall bottled beverages, when needed, without depriving the user of valuable shelf food supporting surfaces.

35 While the form of embodiment of the invention as herein disclosed, constitutes a preferred form, it is to be understood that other forms might be adopted, all coming within the scope of the claims which follow.

40 What is claimed is as follows:

1. In a refrigerator cabinet, a compartment having an access opening and a door for closing said opening, a shelf arrangement within said compartment providing a food supporting surface or area of predetermined size within said compartment, said shelf arrangement comprising a stationarily mounted shelf portion and a movable shelf portion, means on said stationarily mounted shelf portion for detachably carrying said movable shelf portion, means on said door for detachably carrying said movable shelf portion, said movable shelf portion being adapted to be selectively supported on either means, said movable shelf portion when supported by said means on said stationarily mounted shelf portion forming a complementary part of the shelf arrangement to provide said predetermined food supporting surface or area within said compartment, and said movable shelf portion when supported by said means on said door completing said predetermined food supporting surface or area within said compartment and providing a space adjacent the front edge of said stationarily mounted shelf portion and said door for the reception in a vertical position of tall bottled beverages.

2. In a refrigerator cabinet, a compartment having an access opening and a door for closing said opening, a shelf arrangement within said compartment providing a food supporting surface or area of predetermined size within said compartment, said shelf arrangement comprising a stationarily mounted shelf portion and a movable shelf portion, means on said stationarily mounted shelf portion for detachably car-

rying said movable shelf portion, means on said door for detachably carrying said movable shelf portion, said movable shelf portion being adapted to be selectively supported on either means, said movable shelf portion when supported by said means on said stationarily mounted shelf portion forming a complementary part of the shelf arrangement to provide said predetermined food supporting surface or area within said compartment, and said movable shelf portion when supported by said means on said door completing said predetermined food supporting surface or area within said compartment and providing a space adjacent the front edge of said stationarily mounted shelf portion and said door for the reception in a vertical position of tall bottled beverages, said movable portion of said shelf arrangement having a movable member attached thereto for providing a guide-rail therefor when same is carried by said means on said door.

3. In a refrigerator cabinet, a compartment having an access opening and a door for closing said opening, a shelf arrangement within said compartment, means for supporting said shelf arrangement within said compartment, said shelf arrangement including two portions, the one portion of said shelf arrangement disposed adjacent the access opening to said compartment being movable relative to the other portion thereof, means on said door for detachably carrying said movable shelf portion, said movable shelf portion being adapted to be selectively supported on either means, said movable shelf portion when supported by said first named means within said compartment being disposed in substantially the same horizontal plane with said other shelf portion and forming a complementary part of the shelf arrangement to provide a predetermined food supporting surface or area within said compartment, and said movable shelf portion when supported by said means on said door completing said predetermined food supporting surface or area within said compartment and providing a space adjacent the front edge of said other shelf portion and said door for the reception in a vertical position of tall bottled beverages.

4. In a refrigerator cabinet, a compartment having an access opening and a door for closing said opening, a shelf arrangement within said compartment, means for supporting said shelf arrangement within said compartment, said shelf arrangement including two portions, the one portion of said shelf arrangement disposed adjacent the access opening to said compartment being movable relative to the other portion thereof, means on said door for detachably carrying said movable shelf portion, said movable shelf portion being adapted to be selectively supported on either means, said movable shelf portion when supported by said first named means within said compartment being disposed in substantially the same horizontal plane with said other shelf portion and forming a complementary part of the shelf arrangement to provide a predetermined food supporting surface or area within said compartment, and said movable shelf portion when supported by said means on said door completing said predetermined food supporting surface or area within said compartment and providing a space adjacent the front edge of said other shelf portion and said door for the reception in a vertical position of tall bottled beverages, said movable portion of said shelf arrangement having a movable member attached thereto for pro-

viding a rail therearound when same is carried by said means on said door.

5. In a refrigerator cabinet, a compartment having an access opening and a door for closing said opening, a shelf arrangement within said compartment, means for supporting said shelf arrangement within said compartment, said shelf arrangement including two portions, the one portion of said shelf arrangement disposed adjacent the access opening to said compartment being 5
5 movable relative to the other portion thereof, means on said door for detachably carrying said movable shelf portion, said movable shelf portion being adapted to be selectively supported on either means, said movable shelf portion when supported by said first named means within said compartment being disposed in substantially the same horizontal plane with said other shelf portion and forming a complementary part of the shelf arrangement to provide a predetermined food supporting surface or area within said compartment, said movable shelf portion when supported by said means on said door completing said predetermined food supporting surface or 10
10 area of said shelf arrangement within said compartment and being movable outwardly of the compartment when said door is opened.
15. In a refrigerator cabinet, a compartment having an access opening and a door for closing said opening, a shelf arrangement within said 15
15 compartment being movable relative to the other portion thereof, means on said door for detachably carrying said movable shelf portion, said movable shelf portion being adapted to be selectively supported on either means, said movable shelf portion when supported by said first named means within said compartment being disposed in substantially the same horizontal plane with said other shelf portion and forming a complementary part of the shelf arrangement to provide a predetermined food supporting surface or area within said compartment, said movable shelf portion when supported by said means on said door completing said predetermined food supporting surface or 20
20 area of said shelf arrangement within said compartment and being movable outwardly of the compartment when said door is opened.
25. In a refrigerator cabinet, a compartment having an access opening and a door for closing said opening, a shelf arrangement within said 25
25 compartment being movable relative to the other portion thereof, means on said door for detachably carrying said movable shelf portion, said movable shelf portion being adapted to be selectively supported on either means, said movable shelf portion when supported by said first named means within said compartment being disposed in substantially the same horizontal plane with said other shelf portion and forming a complementary part of the shelf arrangement to provide a predetermined food supporting surface or area within said compartment, said movable shelf portion when supported by said means on said door completing said predetermined food supporting surface or 30
30 area of said shelf arrangement within said compartment and being movable outwardly of the compartment when said door is opened.

6. In a refrigerator cabinet, a compartment having an access opening and a door for closing said opening, a shelf arrangement within said

compartment, means for supporting said shelf arrangement within said compartment, said shelf arrangement including two portions, the one portion of said shelf arrangement disposed adjacent the access opening to said compartment being 5
5 movable relative to the other portion thereof, means on said door for detachably carrying said movable shelf portion, said movable shelf portion being adapted to be selectively supported on either means, said movable shelf portion when supported by said first named means within said compartment being disposed in substantially the same horizontal plane with said other shelf portion and forming a complementary part of the shelf arrangement to provide a predetermined food supporting surface or area within said compartment, said movable shelf portion when supported by said means on said door completing said predetermined food supporting surface or 10
10 area of said shelf arrangement within said compartment and being movable outwardly of the compartment when said door is opened, said movable portion of the shelf arrangement having a member attached thereto and normally lying in substantially the same horizontal plane therewith, and said member being movable upwardly relative to said movable shelf portion to provide a rail therealong when same is carried by said means on said door.

EDWARD B. NEWILL. 30
